(57) **CLAIM**

The ornamental design for a Portable Vocal Recording Booth as shown and described.

DESCRIPTION

FIG. 1 is a perspective view of a Portable Vocal Recording Booth showing the new design;

FIG. 2 is a front elevational view of the embodiment of FIG. 1;

FIG. 3 is a rear elevational view of the embodiment of FIG. 1;

FIG. 4 is a right side elevational view of the embodiment of FIG. 1;

FIG. 5 is a left side elevational view of the embodiment of FIG. 1;

FIG. 6 is top plan view of the embodiment of FIG. 1;

FIG. 7 is a bottom plan view of the embodiment of FIG. 1;

FIG. 8 is a perspective view of the embodiment of FIG. 1 having a cap and skirts covering the frame;

FIG. 9 is a front elevational view of the embodiment of FIG. 1 having a cap and skirts covering the frame;

FIG. 10 is a rear elevational view of the embodiment of FIG. 1 having a cap and skirts covering the frame;

FIG. 11 is a right side elevational view of the embodiment of FIG. 1 having a cap and skirts covering the frame;

FIG. 12 is a left side elevational view of the embodiment of FIG. 1 having a cap and skirts covering the frame;

FIG. 13 is top plan view of the embodiment of FIG. 1 having a cap and skirts covering the frame; and

FIG. 14 is a bottom plan view of the embodiment of FIG. 1 having a cap and skirts covering the frame.

Surface shading is used to shade FIGS. 1-14 to show clearly the character and contour of all surfaces of the 3-dimensional aspects of the design and form a part of the design sought to be protected. The cap and skirts are removed in FIGS. 1-7 to show the design of the frame underneath.

1 Claim, 14 Drawing Sheets
